PAVING BLOCK AND PAVEMENT

Dwight W. Longfellow, Elk River, Minn., assignor
to Elk River Concrete Products Company, Elk
River, Minn., a corporation of Minnesota

Application May 3, 1940, Serial No. 333,124

2 Claims. (Cl. 94—11)

My present invention provides primarily an improved paving block, and secondarily, an improved pavement laid or made up of these blocks.

Generally stated, the invention consists of the novel devices, combinations of devices, and arrangement of parts hereinafter described and defined in the claims.

This invention is directed particularly to the provision of an improved concrete pavement made up of monolithic paving blocks especially adapted for use in stockyards, barns, and the like, where a relatively non-skid surface for the travel of livestock is desired.

As is well known, livestock such as cattle, hogs, and sheep, will slip and frequently fall on a smooth concrete pavement or the like and that to prevent such slipping, an irregular surface should be provided. Moreover, the irregular surface should be such that the animals' hoofs will not be caught in depressions. Also, the raised surfaces should be of such extent that they will afford a surface on which the animal may, on occasion, lie with a fair degree of comfort even when slough or bedding is not laid and on which pavement, if bedding is applied, will be quite frequently held against slipping or sliding.

The invention is illustrated in the accompanying drawing wherein like characters indicate like parts throughout the several views.

Referring to the drawing:

Fig. 1 is a view in perspective showing one of the blocks that are adapted to be laid to form the non-skid pavement;

Fig. 2 is a plan view showing the manner in which the blocks are preferably laid to form the pavement;

Fig. 3 is a section taken on the line 3—3 of Fig. 2; and

Fig. 4 is a section taken on the line 4—4 of Fig. 2.

The paving block, indicated as an entirety by the numeral 5, is provided with a raised portion 6 cast integral therewith. The marginal edge of the raised portions 6 are, for an important purpose, bevelled, as indicated at 6', so that when the blocks are laid in overlapping arrangement, there will be drainage passages between the overlapping portions of the blocks, and, moreover, there will be formed channels with which the hoofs of the animals may engage slightly to prevent slipping, note particularly Fig. 3. The numeral 7 indicates the flat upper surfaces of the blocks 5 that extend beyond the raised portions 6.

The exact dimensions of the blocks may, of

course, be varied, but there is an advantage in making the same in substantially the following dimensions, to wit: length of block 16 inches, twice that of the standard brick; width of block 5 4 inches or the same width as an ordinary brick; depth of block 2 inches or the same as that of the standard brick; and length of raised portions 6, 8 inches or the same as that of a standard brick. Moreover, the raised portions 6 should terminate about equi-distant from the ends of the block leaving flat lower surfaces 7 extending 4 inches beyond the ends of the raised portions.

In forming the pavement shown in Fig. 2, the blocks are laid in overlapping arrangement so that the raised portions 6 of the blocks of the one row will be at the longitudinal center of the raised portion of an adjacent row, and the ends of the blocks of one row will be approximately aligned with an end portion of the raised portion 6 of an adjacent row.

By reference to Fig. 2 is shown the preferred manner of laying the blocks, the blocks of a third row, for example, will be aligned with blocks of the first row, and the blocks of the second row will be aligned with the blocks of a fourth row, and so on. This leaves lower surfaces 7 of the blocks forming channels that extend across the flooring.

While the manner of laying the blocks may be varied, they should be laid in an overlapping arrangement so that not only the bodies of the blocks but the raised portions of the blocks of adjacent rows will overlap.

The improved blocks above described having top or raised intermediate surfaces or portions, tend to prevent maximum pressure being applied on the ends of the blocks when the pressure is applied by fairly large objects, such as the hooves of cattle, hogs, or sheep. In the improved arrangement the maximum pressure will be applied to the raised central or intermediate portions of the blocks and this maximum pressure, thus applied on the raised surfaces, will be distributed more or less uniformly over the entire bottom surface of the block, thereby reducing the bearing pressure at the end of the block, and preventing the tipping of the block which is frequently found where the full weight comes on the end of an ordinary plain paving block. The improved design gives sufficient space between the elevated areas so that the hoof of an animal will come up against the sides thereof and definitely prevent slipping. The spaces between the raised areas is sufficient to allow the lower lev-

els, as well as the raised surfaces, to be easily "flushed off" and cleaned.

Another advantage is that the pattern of the paving can be varied to suit different conditions. However, the preferred design is obtained by staggering the successive rows as they are laid so that their raised areas of the blocks in the second adjacent row will be offset one-half the length of the raised area, while the third row lines up with the first.

Still another advantage gained in the use of the improved blocks is that the ends of the blocks being depressed make it difficult or impossible for a hog to get its nose down to the end of the block and loosen it up. Hogs have been known to get one block of the older form of pavement loose and then quickly root up a large area of the pavement. The blocks being larger than ordinary bricks can be laid faster and because of the structure of the block itself, makes a more permanent pavement.

What I claim is:

1. A pavement made up of a multiplicity of elongated rectangular paving blocks formed with raised intermediate surfaces that are approximately one-half the length of the respective blocks and are located substantially equi-distant from the ends of said blocks, said raised portions being of a length approximately equal to the added length of the end portions thereof, the said blocks being laid in rows with the raised portions of adjacent blocks lapping one-half the length thereof and with the upper faces of the end portions also lapping with the raised portions of the blocks in adjacent rows, thereby forming zigzag channels extending transversely of the rows.
2. The structure defined in claim 1 in which the sides of the raised portions of said blocks are beveled upwardly from the plane of the faces of the end portions of said blocks, thereby forming narrow substantially V-shaped drainage passages between overlapping portions of said raised portions.

DWIGHT W. LONGFELLOW.
